Invator-
Lemoy Liddell,
By B. Glaser, Atty.

UNITED STATES PATENT OFFICE.

LENNOX LIDDELL, OF GLASGOW, SCOTLAND.

FILE OR BINDER FOR LETTERS, DOCUMENTS, OR OTHER SHEETS OR PAPERS.

Application filed April 8, 1920. Serial No. 372,804.

To all whom it may concern:

Be it known that I, LENNOX LIDDELL, of 3 Clifton Place, in the county of the city of Glasgow, Scotland, agent, have invented 5 certain new and useful Improvements in and Connected with Files or Binders for Letters, Documents, or other Sheets or Papers, of which the following is a specification.

- 10 My invention relates to improvements in binders for letters, documents, or other sheets or papers, and has for its object to provide an improved binder, which is cheap, efficient and easily applied, and in which 15 any document can be withdrawn and again inserted into the place from which it was removed, all as hereinafter described with reference to the drawings and pointed out in the claim.
- 20 In order that my invention may be properly understood and readily carried into effect, I have hereunto appended drawings, in which:—

Fig. 1 is a front elevation illustrating my 25 invention.

Fig. 2 is also a front elevation in the act of increasing or withdrawing a document or sheet.

Fig. 3 is an end view.

- 30 In carrying out my invention, I provide a channel bar A, in the channel of which is a locking bar B arranged for longitudinal movement and having slots which register with openings in the sides of the channel 35 bar A. Needle points C project from the body of the locking bar into one end of said slots. An arm or handle E for operating the locking bar, is pivoted at D in the channel bar which is provided with a slot at its 40 rear edge to allow the arm to swing in between the sides of the channel bar. To the channel bar A is connected a board F which may be of any suitable material, and which forms the cover of the file. Passing through 45 the cover F and bar A and the back of the file is a cord G, preferably endless and pleated.

The letters, documents or other sheets or papers H are placed between the cover F and back, over base I in the usual manner 50 and the cord G pulled tight. The arm or handle E pivoted to the channel bar at D, is then pressed between the sides of the same, and in so doing causes the pointed ends C to force their way into the cord G 55 and so firmly retain the documents in their place, as seen more particularly in Fig. 1.

When it is desired to remove any document H or insert any fresh ones, the arm or handle E is pulled out, as in Fig. 2, and in 60 so doing moves the locking bar so as to withdraw the pins C from the cord G and so enable the file to be opened and documents to be inserted or removed, as may be desired. 65

A lock may be provided to prevent the file being opened.

By my improvements there are no obstructionable parts to be in the way as with many others in existence. 70

Claim:

In a binder, a channel bar to receive one edge of a cover and having openings in its sides, a base also having openings, a locking bar arranged for longitudinal movement in the channel of the channel bar and having slots which register with the openings of the channel bar and also having needle points projecting into said slots at one end thereof, a binding cord passing 75 through the openings of the channel bar and base and also through the slots of the locking bar, and an operating lever for the locking bar, arranged in the channel of the channel bar and also in a recess in one side of 80 the locking bar, and serving to move the locking bar to cause the points thereof to enter the binding cord. 85

In testimony whereof I affix my signature in presence of two witnesses.

LENNOX LIDDELL.

Witnesses:

JOHN LIDDLE,
JOHN TRAIN LIDDLE.
